UNITED STATES PATENT OFFICE.

WENDELL P. BOSWORTH, OF BROCKTON, MASSACHUSETTS, ASSIGNOR TO BROCKTON HEEL COMPANY, OF BROCKTON, MASSACHUSETTS, A CORPORATION OF MASSACHUSETTS.

MACHINE FOR ASSEMBLING HEEL-LIFT SECTIONS.

No. 923,485.

Specification of Letters Patent.

Patented June 1, 1909.

Application filed January 2, 1908. Serial No. 409,022.

To all whom it may concern:

Be it known that I, WENDELL P. BOSWORTH, of Brockton, in the county of Plymouth and State of Massachusetts, have invented certain new and useful Improvements in Machines for Assembling Heel-Lift Sections, of which the following is a specification.

This invention has for its object to provide a machine for quickly and conveniently assembling and pressing together the parts of the compound heel lift shown in Letters Patent of the United States No. 867,909, granted to William F. Bostock, October 8, 1907. The said heel lift is composed of two general parts, viz., a pieced lift made up of pieces or sections which are abutted together edge to edge and form a lift body, and a thin continuous connecting lift which is placed upon and covers one side of the pieced lift, the said parts being united by cement interposed between the abutting edges of the sections of the pieced lift and between the inner side of the connecting lift and the corresponding side of the pieced lift.

To these ends my invention consists in the construction and combination of parts substantially as hereinafter described and claimed.

Of the accompanying drawings forming a part of this specification, Figure 1 represents a top plan view of a machine embodying my invention. Fig. 2 represents a section on line 2--2 of Fig. 1. Fig. 3 represents a section on line 3--3 of Fig. 1. Fig. 4 represents a perspective view showing the pieced lift and the connecting lift, the said parts being represented by full lines as separated from each other, and by full and dotted lines as assembled.

The same letters of reference indicate the same parts in all the figures.

A machine embodying my invention as here shown includes a circular table *a* which is preferably of annular form and is supported by arms *b* radiating from a central hub *c*, which is mounted to rotate freely on a vertical spindle or bearing *d* having a collar or enlargement *d'* at its lower portion which supports the weight of the carrier. In this embodiment of the invention certain portions of the table *a*, viz., those portions which are partially bounded by the fixed gates *e e'* constitute beds *a'* adapted to support the sections *ff* of the pieced lift or lift body. It

is obvious however that the beds *a'* may be made in separate parts or pieces secured in any suitable way to the carrier.

Each bed *a'* and the accompanying gages *e e'* constitute a part of an organism for acting on a single compound lift, the other parts of the organism being as follows:—*g* represents an edge presser which is movable over the bed *a'* and in direction substantially parallel therewith toward and from the gages *e e'*, the presser *g* being normally forced by spring pressure toward said gages, the arrangement being such that when the lift sections *ff* are placed upon the bed *a'* between the gage *e'* and the edge presser *g*, this being permitted by the retraction of the edge presser against the force of its spring, the edge presser will force the pieced lift toward the gage *e'* and thus press the adjacent edges of the sections *ff* closely together. Said edges are coated with cement before they are placed on the bed, and the operator in applying them to the bed presses their rear ends against the gage *e*. He then releases the presser *g*, the latter pressing one side edge of the pieced lift against the gage *e'*.

h represents a presser foot which is movable toward and from the bed *a'* and is adapted to cover the thin connecting lift *f'*, said lift having been deposited by the operator upon the sections *ff* after the latter have been positioned between the gages *e e'* and the edge presser *g*. The upper surfaces of the sections *ff* or the under surface of the connecting layer *f'* or all of these surfaces, are coated with cement, so that when the presser foot is brought down upon the connecting lift *f'* it causes the adhesion of the latter to the sections *ff*. The presser foot *h* is provided with a resilient shank *h'* which is preferably a curved strip of spring steel. Said shank is movable endwise and is guided or controlled in its movements by guides *i i'* which are rigidly affixed to the carrier, said guides being preferably the forked ends of a standard *i* attached to the carrier. The guide *i* has a slot *i* through which the shank *h'* passes. The guide *i'* has a recess *i'*, the bottom of said recess forming a bearing for the shank, while the sides of the recess guide the shank in its movements.

When the presser foot and shank are moved to the position shown in Fig. 3, the shank is put under tension by its bearing on the bottom of the recess *i'* and on the upper

side of the slot i^3 , this tension being sufficient to cause the presser foot to exert the required pressure on the connecting lift f' . When it is desired to remove the presser foot from its operative position, the shank is moved endwise in the guides until the shank and foot are in the position shown by dotted lines in Fig. 3, and by full lines at the lower portion of Fig. 1.

10. The gages e e' are preferably adjustably secured by means of screws k , the gage e having a slot e^2 which permits longitudinal adjustment of the gage e . The gage e' is adapted to swing on its confining screw when the latter is loosened, so that said gage may be moved laterally over the bed. The edge presser g is here shown as mounted on the free end of a resilient arm g' , which is supported by a screw g^2 , said arm g' normally tending to force the edge presser g toward the gages e e' . If desired the spring arms g' of two adjacent edge pressers g may be made in one piece, having convolutions g^3 wound about two adjacent screws g^2 and a connecting portion g^4 between said screws. The convolutions g^3 are free to expand and contract, and form a part of the spring which acts on the edge presser g .

From the foregoing and by reference to the drawing, it will be seen that the machine may be operated as follows: The operator standing at one side of the machine and at a point which may be considered the front of the machine, brings each of the described organisms successively to the point where he is located, by suitably moving the carrier. Assuming that all the organisms are charged with compound lift parts ff and f' , the operator removes the compound lift which has been for a sufficient length of time under pressure, and then while holding the edge presser g in a retracted position, places the sections of the pieced lift on the bed with the back edge of the pieced lift bearing against the gage e . He then releases the edge presser g , and the latter bears against the opposite side edge of the pieced lift, and forces the latter toward the gage e' . The pressure thus applied to the pieced lift is sufficient to force the abutting edges of the sections together. The operator then applies the connecting lift f' to the upper side of the pieced lift, and then moves the presser foot h downwardly upon the connecting lift, so that the latter is held with sufficient pressure against the pieced lift. The operator then gives a partial movement to the carrier, bringing another completely pressed lift, to the operating station, where the same operation is repeated. The parts of each compound lift after being assembled as above described, remain under pressure during a complete rotation of the carrier, so that time is afforded for the setting of the cement, the

operation of the machine being practically 65 continuous.

I claim:

1. A heel lift assembling machine, comprising a bed, fixed means thereon for supporting the back edge and one side edge of a pieced lift on the bed, a resilient edge presser movable in a direction parallel with the bed, and adapted to engage the opposite side edge of said lift, a presser foot having a resilient shank, which is movable endwise to permit the presser foot to be applied to and removed from a connecting lift on the pieced lift, and means for holding the shank under tension when the foot is in its operative position. 80

2. A heel lift assembling machine, comprising a bed, fixed means thereon for supporting the back edge and one side edge of a pieced lift on the bed, a resilient presser movable in a direction parallel with the bed, 85 and adapted to engage the opposite side edge of said lift, a presser foot having a resilient shank which is movable endwise to permit the presser foot to be applied to and removed from a connecting lift on the pieced lift, and guides for said shank adapted to hold the latter under tension when the foot is in its operative position.

3. A heel lift assembling machine, comprising a movable carrier having a series of lift-confining and pressing organisms, each including and carrying with it a bed, fixed means thereon for supporting the back edge and one side edge of a pieced lift on the bed, an edge presser movable in a direction parallel with the bed, and adapted to engage the opposite side edge of the pieced lift, means for forcing the edge presser toward the side edge support, a presser foot movable toward and from the bed, and means 105 for exerting pressure on said foot to press a connecting lift against the pieced lift, the said organisms being brought successively to the front of the machine by movements of the carrier and exerting practically uniform 110 pressure during the travel of the carrier.

4. A heel lift assembling machine, comprising a rotatable circular carrier, having a series of beds, means movable with the beds for confining and exerting edgewise pressure 115 on pieced lifts supported by the beds, a series of presser feet movable toward and from the beds and also movable with them, means for exerting pressure on said feet to press connecting lifts against the pieced lifts continuously during the travel of the carrier, and means for rotatively supporting the carrier. 120

5. A heel lift assembling machine, comprising a rotatable circular carrier, having a series of beds, means for confining and exerting edgewise pressure on pieced lifts supported by the beds, standards affixed to the carrier and provided with shank guides, a 125

series of presser feet having resilient shanks | slidingly engaged with said guides, and means for rotatively supporting the carrier.

6. A heel lift assembling machine, comprising a rotatable circular carrier having a series of beds, a fixed gage on each bed adapted to engage portions of pieced lifts, a spring impelled edge presser movable on each bed relatively to its gage to position and confine the pieced lifts on the bed, presser feet mounted to rotate with the carrier and movable toward and from the beds,

means for exerting pressure on said feet to press connecting lifts against the pieced lifts continuously during the travel of the carrier, and means for rotatively supporting the carrier. 15

In testimony whereof I have affixed my signature, in presence of two witnesses.
